United States Patent Office

Des. 227,166

Patented June 5, 1973

227,166

COMPACTOR

Eugene C. Briggs and Lee E. Reichel, Dayton, Ohio,
assignors to Koehring Company, Milwaukee, Wis.

Filed Sept. 15, 1971, Ser. No. 180,933

Term of patent 14 years

Int. Cl. D15—04

U.S. Cl. D60—1

FIG-5

FIG. 1 is a perspective view of a compactor embodying our design;

FIG. 2 is a side elevation view of the compactor shown in FIG. 1 taken from a side opposite that illustrated in FIG. 1;

FIG. 3 is a rear end view of our compactor design;

FIG. 4 is a front end view thereof; and

FIG. 5 is a perspective view of a modification of the design illustrated in FIGS. 1 through 4 inclusive.

We claim:

The ornamental design for a compactor, substantially as shown and described.
